US0D1098839S

(12) United States Design Patent (10) Patent No.: US D1,098,839 S
(45) Date of Patent: * Oct. 21, 2025

(54) ICE BUCKET

(71) Applicant: NINGBO HAIYI INDUSTRY CO., LTD., Ningbo (CN)

(72) Inventor: Jiaqi Yan, Ningbo (CN)

(73) Assignee: NINGBO HAIYI INDUSTRY CO., LTD., Ningbo (CN)

() Term: 15 Years

(21) Appl. No.: 29/932,088

(22) Filed: Mar. 12, 2024

(51) LOC (15) Cl. 07-10

(52) U.S. Cl.

USPC D7/605

(58) Field of Classification Search

CLAIM

The ornamental design for an ice bucket as shown and described.

DESCRIPTION

FIG. 1 is a top perspective view of an ice bucket showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a top perspective view of the ice bucket in another configuration of use.

The broken lines in the drawings depict portions of the ice bucket that form no part of the claimed design.

1 Claim, 8 Drawing Sheets
